UNITED STATES PATENT OFFICE.

HARRY E. CAMPBELL, OF NEW YORK, N. Y.

SUPPORT FOR STEAM-RADIATORS.

1,266,210.

Specification of Letters Patent.

Patented May 14, 1918.

Application filed April 6, 1917. Serial No. 160,263.

To all whom it may concern:

Be it known that I, HARRY E. CAMPBELL, a citizen of the United States, residing at New York, in the county of New York and State 5 of New York, have invented a certain new and useful Improvement in Supports for Steam-Radiators, of which the following is a specification.

The invention relates to supports for 10 steam radiators, such as are used in buildings for heating purposes. Such radiators usually rest upon the floor, so that access under them for cleaning purposes or for fitting carpets is difficult. Furthermore, it is 15 often desirable to remove the room radiators, especially in hotels, for purposes of repair, or during the summer months. My present invention consists in the combination with a metal window sill of means directly secured to said sill, whereby a radiator may be 20 suspended from said sill and be held in place thereby. I here illustrate my invention in a sectional radiator, wherein the upper transverse bolt which connects the radiator sections together is simply placed in hooks on the ends of the horizontal arms of brackets which are connected to the metal window sill. After the steam or hot water connections are separated, the radiator can be very 25 easily lifted from or suspended on said bracket hooks.

In the accompanying drawings—

Figure 1 is a front elevation of a radiator supported from the window sill, in accordance with my invention. Fig. 2 is a section on the line x, x of Fig. 1. Fig. 3 is a similar section of a modified construction.

Similar letters of reference indicate like parts.

40 A is the inner portion of a metal window sill supported on the building masonry, and having a downwardly turned flange B. On the inner face of said flange are detachably secured by screws C a number of metal brackets D. The upper end of each bracket is preferably seated in a recess in flange B; the body portion extends vertically downward, and has a projection E which bears against the wall. Below said body portion 45 the bracket is bent inwardly, forming a horizontal arm F, in the end of which is a hook G.

The radiator H may be of any known construction, formed in sections, as I, united by 50 a cross bolt J. Said radiator is suspended

from the brackets D, the hooks G of which enter between the sections I and receive the cross bolt J. Instead of attaching the bracket to the outside of the sill, as shown in Fig. 1, I may seat the vertical or body portion thereof in a recess in the masonry inside of the sill flange B, and at the upper end of said body portion provide a flange K, also seated in a recess in said masonry, but attached to the sill by the screw C. It 55 is to be noted that in both the forms shown respectively in Figs. 2 and 3, the bracket is secured to the sill, and not to the masonry, so that the strain due to the weight and leverage of the radiator comes on the sill. 70

I claim:

1. A metal window sill having a plurality of inwardly projecting arms, and means on said arms for suspending a radiator therefrom.

2. A metal window sill having a plurality of inwardly extending arms disposed in the same plane and adapted to receive radiator sections between them, and means on said arms for supporting said sections.

3. In combination with a metal window sill and a wall supporting the same, metal brackets secured to said sill and having downwardly depending portions bearing against said wall, inwardly extending arms 80 projecting from said downwardly depending portions, and means on said arms for suspending a radiator therefrom.

4. A metal window sill, metal brackets secured to said sill and having inwardly extending arms, and means on said arms for suspending a radiator therefrom.

5. A metal window sill, metal brackets secured to said sill and having inwardly extending arms, and suspension hooks on the 95 ends of said arms adapted detachably to receive a radiator.

6. A metal window sill, metal brackets bent to form vertical and horizontal arms, the vertical arms of said brackets being secured to said sill and having projections bearing on the wall below said sill, the said horizontal bracket arms having hooks on their ends adapted to receive a radiator.

In testimony whereof I have affixed my 105 signature in presence of two witnesses.

HARRY E. CAMPBELL.

Witnesses:

GERTRUDE T. PORTER,
MAY T. McGARRY.
